LIPSTICK CONTAINER

John H. Voegeli, Prospect, Conn.

Application October 22, 1946, Serial No. 704,868

6 Claims. (Cl. 206—56)

1

This invention relates to cosmetic holders, and more particularly to an improved container for a lipstick crayon or pencil having a pair of pivoted covers to enclose said crayon when not being used.

One object of this invention is to provide a lipstick container of the above nature having an improved unitary mechanism for successively opening the pivoted covers and elevating the lipstick crayon.

A further object of this invention is to provide an improved lipstick container of the above nature which will be relatively inexpensive to manufacture, simple in construction, compact, ornamental in appearance, and very efficient and durable in use.

With these and other objects in view, which will appear as the description proceeds, there has been illustrated in the accompanying drawings one form in which the invention may be conveniently embodied in practice.

In the drawing:

Fig. 1 is a side view in elevation of the improved lipstick container with the upper portion of the outer shell shown in section, and with the covers in closed position.

Fig. 2 is a side view similar to Fig. 1 with the covers in open position.

Fig. 3 is a vertical sectional view taken on the line 3—3 of Fig. 2, looking in the direction of the arrows.

Fig. 4 is a cross sectional view taken on the line 4—4 of Fig. 3, looking downwardly.

Fig. 5 is a perspective view of the two covers shown in separated relation.

Fig. 6 is a perspective view of the inside shell.

Fig. 7 is a perspective view of the intermediate shell.

Fig. 8 is a detail sectional view taken along the inclined line 8—8 of Fig. 2, looking toward the left.

Referring now to the drawings in which like reference numerals designate like parts throughout the several views, the numeral 10 indicates the outer casing of the lipstick holder. The casing 10 is provided with an open top dome having an inturned curved rim 11.

Fitted within the bottom of the outer casing 10 is a short cylindrical flange 12 integral with and offset outwardly from an inner shell 13 (Fig. 6). The shell 13 has a wide vertical slot 14 which lies in alignment with a narrow vertical leg 15 of an L-shaped slot 15a formed in the outer casing 10.

Disposed between the outer casing 10 and the inner shell 13 is an intermediate shell 16 (Fig. 7)

2

which has a narrow vertical slot 17 which is aligned with the slots 15 and 14. The shell 16 rests upon the top of the flange 12 of the inner shell 13.

5 A lipstick crayon 18 is tightly seated in a twistable and slidable carrier sleeve 19, having a solid plug 20 tightly mounted within its lower end.

In order to elevate and lower the lipstick-carrying sleeve 19 within the inner shell 13, provision is made of a horizontal stud 21 having a reduced threaded end 22 screwed into the plug 20 and also having an enlarged handle knob 23 located outside the casing 10.

As clearly shown in Fig. 3 of the drawing, the 15 stud 21 passes through the slots 14, 15, 17 and enables the height of the lipstick crayon 18 to be readily adjusted by manipulating the handle knob 23.

20 In order to close the open upper end of the casing 10 after the lipstick sleeve is depressed, provision is made of a pair of identical bucket members 24, 25, each forming a portion of a hollow sphere. Each of the bucket members 24, 25 has a pair of depending ears 26, 27, at the opposite sides thereof.

25 The ears 26, 27 are apertured to rotatably fit upon a pair of opposed outstanding eyelet rivets 28, 29 integral with the inner shell 13. The ears 27 of the buckets 24, 25 have inturned hook lugs 30, 31 formed thereon.

The bucket members 24, 25 are reversely arranged so that the hook lugs 29 thereof are adapted to seat in a pair of outstanding eyelet rivets 30, 31 formed in the upper portion of the 35 intermediate shell 16.

Assembly

The parts of the improved lipstick container may be assembled together by first inserting the 40 carrier sleeve 19 within the inner shell 13. The intermediate shell 16 will then be slipped over the inner shell 13 and the bucket members 24, 25 attached in operating position to the inner shell 13 and the intermediate shell 16. The outer 45 casing 10 will then be slipped down to the position shown in Figs. 1-3 after which the stud 21 will be inserted through the aligned slots 14, 15 and 17 and screwed into the carrier sleeve 19 and the bottom plug 20 located therein.

Operation

50 When it is desired to close the lipstick container, the handle knob 23 will first be slid downwardly as far as it will go to retract the lipstick crayon 18 into the container. The stud 21 will

then be at the bottom of the vertical leg of the L-shaped slot 15. The handle knob 23 will then be swung horizontally to the right as far as it will go, causing the carrier sleeve 19 and the intermediate shell 16 to be rotated and also move the ears 27, 27. This action will cause the bucket members 24, 25 to be rocked from the open position, shown in Fig. 2, to the closed position shown in Fig. 1, upon the eyelet rivets 28, 28 as fulcrum due to the fact that the eyelet rivets 28 remain stationary.

When it is desired to use the lipstick crayon 18, the handle knob 23 will be swung to the left and then upwardly to first open the bucket cover members and then raise the crayon-holding carrier sleeve 19 to the position shown in Fig. 3.

While there has been disclosed in this specification one form in which the invention may be embodied, it will be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a lipstick container, an outer casing, an inner shell rigidly mounted in said casing, a carrier for a lipstick crayon slidably and rotatably mounted within said inner shell, cooperating cover members for the top of said crayon pivoted to said inner shell, means responsive to the twisting of said carrier when in its lowermost position to rock said cover members about their pivots into closed positions, and means for holding said carrier against sliding in said inner shell during twisting movement thereof.

2. In a lipstick container, an outer casing, an inner shell rigidly mounted within said casing and spaced inwardly therefrom, a carrier for a lipstick crayon slidably and rotatably mounted within said inner shell, a rotatable intermediate shell located between said inner shell and said outer casing, a pair of dome-shaped cover members pivoted to said inner shell at the top thereof, said cover members having depending lugs connected to said intermediate shell whereby when said carrier is twisted in its lowermost position, said cover members will be rocked about their pivots to enclose the top of said lipstick crayon, and means

for holding said carrier against sliding in said inner shell during twisting movement thereof.

3. In a crayon container, an outer casing, an inner shell rigidly mounted within said outer casing, a crayon carrier slidable and rotatable within said inner shell, a pair of cooperating swingable dome-shaped cover members pivoted to said inner shell, means responsive to the successive downward sliding of said carrier and the rotation thereof within said casing to successively depress said crayon and close said cover members over the top of said crayon, and means to prevent the sliding and the rotation of said carrier from occurring simultaneously.

15 4. In a lipstick container, an outer casing, an inner shell rigidly secured to said outer casing, a carrier for a lipstick crayon slidably and rotatably within said inner shell, a rotatable intermediate shell located between said inner shell and outer casing, said outer casing, said inner shell, and said intermediate shell having aligned vertical slots, a stud member secured to said carrier, passing through said slots and having an exterior operating handle knob, a pair of bucket cover 20 members fulcrumed on the upper end of said inner shell and having depending lugs pivotally engaged in said intermediate shell, the slots in said outer casing and in said inner shell having portions which are wider than said stud member, whereby the depression of said stud will lower said crayon and the subsequent rotation of said stud will close said bucket and cover members.

5. The invention defined in claim 4, in which 25 the vertical slot in said casing has a horizontal extension at the bottom thereof to permit said intermediate shell to rotate and close said bucket members after said lipstick crayon carrier has been depressed as far as it will go.

6. The invention defined in claim 4, in which the vertical slots in said inner shell is made sufficiently wide as not to be engaged by said stud when the latter is rotated and prevent twisting said carrier and said intermediate shell.

JOHN H. VOEGELI.
